UNITED STATES PATENT OFFICE.

JAMES PETER VANDENORTH, OF CHICAGO, ILLINOIS.

WINDOW-SHADE.

1,106,601.

Specification of Letters Patent. Patented Aug. 11, 1914.

Application filed November 8, 1913. Serial No. 799,925.

To all whom it may concern:

Be it known that I, JAMES PETER VANDENORTH, a citizen of the United States, residing at Chicago, in the county of Cook and State of Illinois, have invented certain new and useful Improvements in Window-Shades, of which the following is a specification.

This invention relates to improvements in window-shades, and its object is to provide a novel and improved structure and mounting which enables the shade to be converted into an awning or sun-shade.

In order that the invention may be better understood, reference is had to the accompanying drawings in which—

Figure 1 is a front elevation of a window showing the invention applied thereto; Fig. 2 is a vertical section on the line 2—2 of Fig. 1; Fig. 3 is a perspective view of the lower portion of the device; Fig. 4 is a longitudinal section on the line 4—4 of Fig. 1; Fig. 5 is a perspective view of a fragment of the bottom bar of the shade, and Fig. 6 is a cross section on the line 6—6 of Fig. 3.

The reference character 5 in the drawings denotes a window frame or casing in which are mounted sliding sashes 6. The shade is a strip 7 of suitable fabric which is connected to a spring-roller 8 supported by brackets 9 at the top of the window frame. The spring-roller is in all respects similar to the spring-rollers employed in connection with ordinary window-shades. Substantially midway between the top and bottom of the window frame, on the same side as the spring roller, is mounted a roller under which the shade is adapted to be passed. The roller comprises two sticks 10 tightly fitted at their inner ends into a sleeve 11. This construction is provided in order that the roller may be lengthened or shortened to suit windows of different widths, adjustment of the roller being readily effected by drawing one or both sticks out of the sleeve more or less, or by pushing the sticks farther back into the sleeve. The roller is supported at its ends by brackets 11 similar to the supporting brackets of the spring roller of an ordinary window-shade.

To each stile of the window frame, at or about the middle of the lower sash 6, is secured the base bar 12 of a vertically swinging bracket arm 13, said bar having an outstanding ear 14 at the top to which the inner end of the bracket arm is pivoted, as

indicated at 15. The bottom of the bar has an outstanding ear 16 to which is pivoted, as indicated at 17, a brace bar 18 having a sliding connection with the bracket arm to permit the latter to be folded downward. The bracket arm has intermediate its ends a longitudinal slot 19 in which works slidably a sleeve 20 on a stud 21 carried by the outer end of the brace bar. The outer end of the bracket arm has a short slot 22, which latter is for a purpose to be presently described.

To the bottom edge of the shade 7 is secured a cross bar 23 composed of several adjustably connected sections to allow lengthening or shortening according to the width of the shade. The ends of the cross bar project slightly from the side edges of the shade, and at the extremity of each of said ends is a reduced portion 24 terminating in a head 25. To the bottom of the shade 7 is attached a cord 26 adapted to be secured to a hook 27 mounted on the window-sill 28.

To operate the shade 7, it is drawn down by means of the cord 26 and passed behind the roller composed of the parts 10 and 11. The bracket arms 13 being in folded position as shown by dotted lines in Fig. 3, the shade is drawn down until the heads 25 may be passed through the slots 22, the width and length of the heads being such that this may be readily done. The heads are elongated in the direction of the length of the shade, hence they will readily pass through the slots when the bracket arms are in depending folded position, as the slots 22 are then vertical and the heads 25, when the shade is pulled straight down, are positioned so that their longest dimensions are vertical. The heads are passed through the slots until the reduced portions 24 lie in the latter. The lower end of the shade is now connected to the bracket arms, and upon releasing the cord 26, the spring roller 8 pulls up the shade, thereby unfolding the bracket arms, the same swinging upward and outward until the connections between the bracket arms and the brace bars 18 reach the inner ends of the slots 19. The bracket arms are now in horizontally projecting position, and the lower portion of the shade extends slantingly downward and outward from the roller composed of the parts 10 and 11, similar to an awning. If the shade is to remain all the way down, the bracket arms will be left in folded position, in which position

their free ends coincide with the bottom of the window frame. If an intermediate position is desired, the shade will be placed in the desired position and held by making 5 the cord 26 fast to the hook 27. The width of the heads 25 is slightly less than that of the bar 23, hence the bracket arms 13 will meet a shoulder at the inner end of the reduced portions 24. It will be noted that 10 when the shade is in the position shown in Fig. 2 the heads 25 will extend at an oblique angle with reference to the slots 22, in view of which, the bar 23 cannot become accidentally disconnected from the bracket arms 15 13. Before disconnection can be made, the heads must be brought into alignment with the slots. To release the shade, the heads 25 need only be turned to pass back through the slots 22, and after disconnecting the 20 shade from the bracket arms 13, the cord 26 is released, whereupon the spring roller 8 will wind up and pull the shade to the top of the window frame. The ears 14 and 16 are located at the opposite edges of the base 25 bar 12, which enables the parts 13 and 18 to fold closely together.

By the structure hereinbefore described, a window shade is had which can readily be converted into an awning or sun-shade, the 30 parts forming the supports of the shade are strong and durable, and there is an entire absence of complicated structural details liable to get out of order.

I claim:

35 1. The combination with a window-shade,

of a transverse member mounted intermediate the top and bottom of the window, behind which member the shade is adapted to be extended, bracket arms pivoted to the window casing below the transverse member to swing in a vertical plane, said bracket arms having slotted free ends, and a cross bar mounted on the lower end of the shade and projecting from the side edges thereof, the projecting ends of the cross bar having 45 a head which is elongated in the direction of the length of the shade, and dimensioned to pass through the slots of the bracket arms.

2. The combination with a window-shade, 50 of a transverse member mounted intermediate the top and bottom of the window, behind which member the shade is adapted to be extended, base bars secured to the window casing, bracket arms below the transverse member, foldable braces having a sliding connection with the bracket arms, the aforesaid base bars having ears to which the bracket arms and the braces are pivoted, the ears to which the bracket arms are pivoted being offset relative to the ears to which the 55 braces are pivoted, and means for connecting the lower end of the shade to the free ends of the bracket arms.

In testimony whereof I affix my signature in presence of two witnesses.

JAMES PETER VANDENORTH.
